UNITED STATES PATENT OFFICE.

EDGAR W. SUMMERS, OF YOUNGSTOWN, OHIO.

METALLIC CAR.

SPECIFICATION forming part of Letters Patent No. 738,128, dated September 1, 1903.

Original application filed March 16, 1901, Serial No. 51,425. Divided and this application filed January 29, 1903. Serial No. 140,968. (No model.)

To all whom it may concern:

Be it known that I, EDGAR W. SUMMERS, of Youngstown, in the county of Mahoning and State of Ohio, have invented a certain new and useful Improvement in Metallic Cars, of which improvement the following is a specification.

The object of my invention is to provide a sheet-metal railway-car which shall combine the characteristics of lightness, strength, and rigidity with those of cheapness of construction and durability in service.

The improvement claimed is hereinafter fully set forth.

15 In the accompanying drawings, Figure 1 is a top plan view of a portion of a car illustrating an embodiment of my invention; Fig. 2, a partial bottom plan of the same; Fig. 3, a vertical longitudinal section; and Fig. 4 a 20 fragmentary vertical transverse section, on an enlarged scale, on the line 7 7 of Fig. 3.

In the drawings, A A represent the sides of the car; B, the floor; C, the end; D, the bolster; E, the draft-beam, and F the draw-head.

25 The draft-beam (indicated by E) is an inverted-U shaped beam. It has a top plate which abuts the under side of the end plate b⁷ of the floor, to which it is secured by numerous rivets e¹, these rivets being countersunk on their upper side to leave a smooth upper surface to the floor. The vertical sides e² of this beam are flanged outward at their inner ends and riveted to the bolster, as shown 30 at e³. At the lower edges the beam is flanged outward, as at e⁴, which lower edges are secured to the flanges d³ of the bolster and to the plate d⁴ and where the draft-beam crosses the end C of the car to the lower end thereof 35 by means of the plates c, which are riveted to the inturned flanges c¹ at the base of the car end and are also riveted to the flanges e⁴ of the draft-beam. This draft-beam lies between a pair of angle-bars c², which are riveted to the car end, and the vertical sides e² of the beam are riveted to the adjacent sides of these angle-bars. The floor-plate b⁷ is turned up and riveted to the end plate of the car.

40 Within the draft-beam is the reinforcing member J, which is preferably a steel casting

of the form shown in Figs. 3 and 4. This casting is secured within the draft-beam by the same rivets which secure the beam to the angle-bars c² and to the outturned flanges c³ 55 of the car end and by some of the rivets which secure the draft-beam to the car-floor b⁷. The casting has strengthening-webs j depending from its upper surface and has inturned flanges j¹ for confining the draw-head F. This 60 draw-head is of any suitable construction. It rests on the plate j², carried between the webs j³ of the steel casting and abutting the under side of the flanges j¹, to which the plate may be secured by bolts. The draw-head is 65 guided by the inturned flanges j¹ and by the downwardly-extending flange j⁴ at the forward end thereof.

It will be observed that in the above-described car I have reduced the weight without sacrificing strength and rigidity. This reduction of weight is a very important factor, since the expense of hauling a load is dependent upon the weight thereof, and the lighter the car the greater the proportion which the 75 paying weight—that is, the freight carried—bears to the whole weight, which means that for the same capacity the efficiency of the car increases with its lightness.

I claim as my invention and desire to secure by Letters Patent—

1. A draft-beam having bottom flanges in combination with the metallic load-retaining end wall-plate of the car which has also a bottom flange, and means for securing said flanges 85 together.

2. The combination of a sheet-metal draft-beam in the form of a U-shaped plate, and a reinforcing-casting within such beam and riveted thereto, said casting and draft-beam being both secured to the end of the car.

3. A hollow sheet-metal draft-beam and a reinforcing-casting within the same which casting has webs or flanges for strengthening it and confining the draw-head, combined 95 with the end of the car, said end and casting and draft-beam being secured together by the same rivets.

4. A metallic car having an end plate and a load-supporting floor leading therefrom, combined with a draft-beam having substantially vertical sides, said beams being secured

to said floor, and the end plate extending down beneath the floor on opposite sides of said draft-beam, and angle-strips lying on opposite sides of said draft-beam and riveted to it and to said end plate.

5. A draft-beam having bottom flanges, in combination with the metallic load-retaining

end wall-plate of the car, which has also an integral bottom flange, and means for securing said flanges together.

EDGAR W. SUMMERS.
